UNITED STATES PATENT OFFICE.

HUGH L. REID, OF PROVIDENCE, RHODE ISLAND, ASSIGNOR TO HOWARD & SCHERRIEBLE, OF SAME PLACE.

DESIGN FOR LETTERS OR ALPHABET.

SPECIFICATION forming part of Design No. 13,681, dated February 27, 1883.

Application filed January 22, 1883. Term of patent 3½ years.

To all whom it may concern:

Be it known that I, HUGH L. REID, a citizen of the United States, residing at Providence, county of Providence, and State of Rhode Island, have invented and produced a new and original Design for an Alphabet or for Letters or Type, of which the following is a specification, reference being had to the accompanying photographic print, forming a part of the specification.

The nature of my design for alphabet or letters is clearly shown in the accompanying photograph, which represents all the letters of my newly-designed alphabet.

15 Each letter of my newly-designed alphabet is composed of one or more narrow lines, either straight or curved, and a scroll, as shown in the photographic illustration referred to. The letters A, H, I, J, K, L, M, N, P, R, U, V, W, 20 X, Y, Z, and & are composed of straight lines and a scroll, a, all the scrolls being inwardly turned except that in the letter K. The letters B C E G P S T are composed of straight and curved lines with the scroll-like ending or ornament a, and the letters O Q S of curved lines and the scroll a. The scrolls a form the leading feature of my design, they being added to the other parts of the lines used in the formation of the letters, as shown in the photograph referred to.

30 I claim—

The design for alphabet or letters, as herein shown and described, the same consisting of the straight and curved lines and the scrolls, substantially as represented.

35 In testimony whereof I have signed my name to this specification in the presence of two subscribing witnesses.
